(57) **CLAIM**

The ornamental design for a urinal as shown and described.

DESCRIPTION

FIG. 1 is a perspective view of a urinal according to the first embodiment, showing our new design;

FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a cross-sectional view taken along line 8-8 in FIG. 2;
FIG. 9 is a cross-sectional view taken along line 9-9 in FIG. 2;
FIG. 10 is a perspective view of a urinal according to the second embodiment, showing our new design;
FIG. 11 is a front view thereof;
FIG. 12 is a rear view thereof;
FIG. 13 is a left side view thereof;
FIG. 14 is a right side view thereof;
FIG. 15 is a top view thereof;
FIG. 16 is a bottom view thereof;
FIG. 17 is a cross-sectional view taken along line 17-17 in FIG. 11;
FIG. 18 is a cross-sectional view taken along line 18-18 in FIG. 11;
FIG. 19 is a perspective view of a urinal according to the third embodiment, showing our new design;
FIG. 20 is a front view thereof;
FIG. 21 is a rear view thereof;
FIG. 22 is a left side view thereof;
FIG. 23 is a right side view thereof;
FIG. 24 is a top view thereof;
FIG. 25 is a bottom view thereof;
FIG. 26 is a cross-sectional view taken along line 26-26 in FIG. 20; and,
FIG. 27 is a cross-sectional view taken along line 27-27 in FIG. 20.

The broken lines in the drawings are for the purpose of illustrating portions of the urinal that form no part of the claimed design.

The dot-dashed lines which define the bounds of the claimed design form no part of the claimed design.

1 Claim, 27 Drawing Sheets
